UNITED STATES PATENT OFFICE.

JOHN SELLERS BANCROFT AND MAURITZ C. INDAHL, OF PHILADELPHIA, PENNSYLVANIA, ASSIGNORS, BY MESNE ASSIGNMENTS, TO LANSTON MONOTYPE MACHINE COMPANY, OF WASHINGTON, DISTRICT OF COLUMBIA, A CORPORATION OF VIRGINIA.

AUTOMATIC LEADER FOR TYPE-COMPOSING MACHINES.

SPECIFICATION forming part of Letters Patent No. 700,288, dated May 20, 1902.

Application filed November 9, 1901. Serial No. 81,716. (No model.)

To all whom it may concern:

Be it known that we, JOHN SELLERS BANCROFT and MAURITZ C. INDAHL, of Philadelphia, in the county of Philadelphia and State 5 of Pennsylvania, have invented certain new and useful Improvements in Automatic Leaders for Type-Composing Machines; and we hereby declare the following to be a full, clear, and exact description of the same, reference being had to the accompanying drawings, forming a part of this specification, and to the figures of reference marked thereon.

The principal object of this invention is to provide a controllable automatic leading attachment for type casting or setting machines—that is, one in which the function of inserting the leads between lines of type, although automatically performed, is subservient to the will of the compositor to such an extent that he can determine and designate in advance the exact point or points where the leading shall begin and terminate.

To this end the invention comprehends the employment, in connection with a type-composing machine (whether type making and setting or type-setting alone) whose action is governed by a controller—such as a perforated record-strip or equivalent—of a leading attachment responsive to said controller and adapted to be thrown into and out of action thereby.

The invention also includes an improved construction of the leader and of the actuating and controlling devices therefor by means 35 of which movements normal to the machine to which it is applied are utilized, all as hereinafter more fully described, the novel features being pointed out in the appended claims.

40 In the accompanying drawings, illustrating the preferred form of embodiment of said invention, Figure 1 is a top plan view of the leading attachment applied in connection with a type casting and composing machine. Fig. 2 is a side elevation of the leader. Fig. 3 is a view in perspective. Fig. 4 is a top plan view. Fig. 5 is an end elevation, and Fig. 6 a vertical longitudinal section, of the

controlling mechanism. Fig. 7 is an end elevation, and Fig. 8 a top plan view, of the 50 leader and its actuating devices. Fig. 9 is a vertical section on line X X of Fig. 8. Fig. 10 is a top plan view of the automatic trip mechanism intermediate the controlling mechanism and the leader proper. Fig. 11 is a detail of the yielding coupling and latch intermediate the lead-delivering plunger and its actuating devices. Fig. 12 is a perspective view of the lead-delivering plunger detached. Fig. 13 is a similar view of the link intermediate the latch and actuating devices. Fig. 14 is a longitudinal vertical section on line 55 Y Y of Fig. 8, showing the disconnecting devices intermediate the leader and its actuating mechanism. Fig. 15 is a perspective view 60 of a section of the leader, showing one of the lead guides and pushers and the connections with the actuating mechanism. Fig. 16 is a longitudinal vertical section through the line-supporting blade. Fig. 17 is a transverse 65 vertical section through said blade and the transfer-bar. Fig. 18 is a perspective view of the line-supporting blade. Fig. 19 is a perspective view of one of the lead-pushers removed. Fig. 20 is a diagrammatic view of 70 a section of the controller or record-strip, showing the special leading-signals. Fig. 21 is a representation of a section of the controller with leading-signals associated with 75 type-signals for a line.

80 Similar numerals in the several figures indicate the same parts.

For purposes of illustration the improved leader is shown as adapted and applied to the galley mechanism of a well-known type 85 casting and composing machine, that of Patent No. 625,998, to which latter reference is made for a more full description. It is sufficient for present purposes to note that 1 is the top or bed plate of the casting-machine; 2, 90 the galley; 3, the main lever for the centering-plunger; 4, the actuating-lever for the die-centering mechanism; 5, the line-transfer bar; 6, the vertically-movable blade at the entrance to the galley; 7, the actuating-lever for said blade, deriving its motion from 95

a cam on the shaft 8 of the galley mechanism, and 9 a reciprocating slide driven from a cam on shaft 8 and actuating the hooked arms 10 of the line-carrier. It is to be remembered that the action of the casting-machine is governed by a perforated record-strip or controller and that the justifying-wedges are each moved into operative relations with the adjusting devices by levers 11, said levers being designated for adjustment by the admission of air through passages 12 13. The galley mechanism is normally at rest and is set in action to remove the completed line of type from the line-channel to the galley by the action of the justifying-wedge-designating mechanism. When started in action, the cams on galley-shaft 8 are given one complete revolution, during which slide 9 is moved first outward or to the right, Fig. 1, then a full excursion inward or to the left, and finally returned to its intermediate position, as indicated by full lines in Fig. 10 and by dotted lines in Fig. 2. During these movements blade 6 is elevated to uncover the entrance to the galley, and line-transferrer 5 is advanced to force the completed line (previously brought to position by the line-carrier) under blade 6 and into the galley, after which said blade again descends to position.

The foregoing brief summary will be of assistance in understanding the application of the present invention. The leader proper embraces the means for delivering leads, one at a time, to the galley, in rear of the last line of type inserted therein, and were it not for obstructing the galley or rendering the apparatus difficult of access it might be located in close proximity to the galley-entrance and either above or below the latter; but in applying it to an already-existing mechanism it is found expedient to locate it to one side of and above the galley. To this end the leader is arranged above and in rear of the galley-blade 6, Fig. 7, and to one side of the galley. It comprises a bed plate or frame 20, mounted on posts 21, secured to the galley-frame and provided with two oppositely-grooved uprights or housings 22, forming a channel for the reception of a column of leads. One of the housings 22 is fixed in position, and the other is rendered adjustable with relation thereto, as by a screw-bolt 23, engaging a nut 24, Fig. 14, the latter received in an undercut groove 25, extending longitudinally of the bed-plate 20. This is to permit adjustment to accommodate leads of different length. Attached to the lower end of the rear flange 26 of each housing 22 is a horizontal bar 27, forming the floor of the lead receptacle or channel and serving to sustain the lower lead a slight distance above the frame. The lower end of the flange 26 is also slotted for the reception of the pusher 65 and its guide-bar, and the opposite flange 28 is likewise slotted to permit the passage of a

lead, said slot being equal in width to the thickest lead employed.

The lead-pushers, of which two are preferably employed, one for each housing, each comprises a horizontal spring-blade 30, secured at one end to a bar 31, guided to reciprocate in ways in the lower end of the housing, the opposite end being cut away on its upper surface to form a slightly-undercut shoulder 32. When the pusher is retracted, said shoulder stands just in rear of the inner surface of flange 26, the reduced end of the pusher extending beneath the lowest lead. The forward or free end of the pusher is curved slightly to cause its engaging end to bear against the under surface of the lead resting upon the floor of the channel, so that when retracted the shoulder will stand above and be held in position to engage the rear edge of the lower lead, and when the pusher is advanced it will drive said lead out through the slots in the opposite flanges 28. To adapt the device for operating upon all thicknesses of leads, the shoulder 32 is formed of a height equal to or slightly less than the thickness of the thinnest lead, and the discharge-opening in the opposite flange 28 equals or slightly exceeds the thickness of the thickest lead employed. Hence to avoid discharging more than one lead at a time when the thinner varieties are employed a cut-off is located at the discharge-opening. This consists in the present instance of two bars 33, one for each housing, mounted upon links 34 and held pressed downward or toward the floor 27 of the channel by a spring 35. The lower ends of the bars 33 are beveled and projected inward toward the discharge-orifice, so that they will yield readily to the advance of the lower lead under the influence of the pushers, but only sufficient to permit the escape of said lead, the springs holding them down upon the upper surface of the lead by which they were moved, so as to prevent the escape of the superposed lead or leads contained in the channel. The forward motion of the pushers 30 is sufficient in extent to carry the engaging shoulders 32 beyond the cut-off 33 and deliver the lead into the mouth of a vertical conductor 36 in line with the galley-blade 6, said conductor being formed between the outwardly and downwardly curved face 37 of bed-plate 20 and a plate 38, secured to the latter.

The galley blade or rule 6 instead of being solid, as heretofore, is provided with a longitudinal channel 39, which is closed at the inner end in line with the inner wall of the galley. The bottom of this channel is omitted or cut away opposite the galley, while the top is omitted along the outer section, or that standing immediately below and in line with conductor 36, and the leads as they fall from said conductor enter and are received within the blade 6.

Supported on ways 40, attached to blade 6,

is a slide 41, to which is adjustably secured a pusher-blade 42, the latter working within channel 39 and furnished with an expansible head 43 for engaging the lead after it has been received in the channel and transferring it to the inner end of the blade opposite the galley, thus bringing it into position to enter the galley in front of the next succeeding line of type when blade 6 is elevated for the purpose.

The feeding motion of the lead-pushers 30 is in the present instance derived from the vertically-movable blade 6 and coincides therewith. It will be remembered that blade 6 rises to admit the completed line to the galley. This motion is transmitted to the pushers 30 through a lever 44, connected through link 45 to an arm 46, fast to shaft 47. This shaft carries two arms 48, of which the outer 20 one is adjustable, each furnished with a fork engaging a pin 49 on its pusher-bar 31. A spring connected to lever 44 serves to retract the pusher and hold it in position with its engaging shoulder in rear of the lower lead. If 25 the lever 44 were engaged directly by the blade 6, the device would operate as a constant feeder, a lead being discharged each time a line was introduced into the galley; but to increase its capacity for automatic control, as 30 well as to furnish means for readily throwing it out of action when desired, a disengaging device is interposed. In the present instance this is introduced in the form of a pin 50, supported to rotate and reciprocate in a bearing 35 formed in bed-plate 20, and provided with an arm 51, in position to enter a notch 52 in a block fast on blade 6. When pin 50 is turned to engage notch 52, it will accompany blade 6 in its vertical motions and operate the lead-40 feeder, but when withdrawn from the notch the blade is free to move while the leader remains at rest. The reciprocating motions of pusher-blade 42 are transmitted from slide 9 of the line-carrying devices through a yielding and detachable connection, yielding to 45 prevent damage should the pusher become jammed, and detachable for the ready removal of the pusher-blade. In the present adaptation there is secured to the slide 9 a plate 55, bearing a segment 56, and an arm 57, pivoted at 58 on said plate and provided with a guide 59, embracing the segment, Fig. 2. Arm 57 is provided with a shoulder 60, Fig. 11, between which and a spring-actuated pivoted 55 dog 61 is secured a pin 62 on slide 41. This arrangement not only accommodates the rise and fall of the galley-blade 6, but it effects a slight retraction of the pusher 42 as the blade 6 is elevated, a special feature of accommodation to existing dimensions for increasing the throw of the pusher.

It will be noted that the movements of the parts selected for operating the lead-feeding pushers 30 and translating-pusher 42 are well adapted for the purpose had in view—to wit, the insertion of a lead behind each completed line of type as the latter is delivered to the

galley. Thus the bringing of the line of type opposite the galley is accompanied by a retraction of pusher 42, the elevation of the 70 blade 6 to admit the line feeds a lead from the holder and delivers it within the blade 6, and the descent of said blade and return of the line-carrier to position advance the lead to place in rear of the line of type last advanced into the galley. It is further to be noted that while the record-strip or controller is prepared in the order of composition it is fed to the type casting or composing machine in the reverse order. Consequently although 80 the lead thus inserted occupies a position in rear of the last line as the column is built up in the gallery it, in fact, precedes the line of matter as composed on the controller and printed or read from the type. The significance of this will later appear.

As thus far described the apparatus is adapted to automatically insert a lead with each line of type delivered to the galley, its automatic action being dependent, however, 90 upon the galley mechanism, although susceptible of intentional interruption, as when the operator disconnects the lead-feeding devices from its driving mechanism; but it not infrequently happens that the compositor finds it 95 necessary or desirable to insert a lead or leads between certain lines only, or to lead a given paragraph or section of the column, leaving the balance solid. With the leader described applied to the composing-machine it would 100 be possible for him to indicate on the controller or otherwise signal the operative when to connect and disconnect the leading attachment; but such a scheme would necessarily 105 be unreliable, as involving a concurrence of action on the part of the compositor and the attendant at the composing-machine, and it is in part for the purpose of avoiding this and other defects in such a system that the present arrangement has been devised. The 110 proposition is to place the leading action under the direct control of the compositor, who prepares the controller or record-strip, and this is accomplished by making the controller itself the governing agent of the leader, as it 115 has heretofore been of the composing mechanism, so that the compositor may designate just where and when the leads shall be supplied to the galley.

It is obvious that in carrying out this invention various forms of transmitting and controlling mechanisms may be interposed between the controller and leading attachment for this purpose, and that about to be described may be taken as illustrative of one 125 of the preferred embodiments adapted for application to an existing type of machine. First, as to the controller. It is only necessary to provide it with a distinctive signal or perforation operative in the composing-machine to govern the starting and stopping of the leader, as desired. For economical reasons these signals, instead of standing alone and thus entailing a non-productive revolu-

tion of the driving-shaft, are preferably associated with the justification-signals, inasmuch as the latter occupy a position between lines, where the leading is to occur, are in multiple, affording opportunities for differentiating between the starting and stopping, and involve the temporary suspension of the type-casting function. In the present instance the leading-signal is composed of any one of the numerous signals or perforations designating lines in the die-case in association with either one of the justification-wedge-designating signals or perforations, one of the latter for designating stoppage, and the other action of the leader. Thus the starting-signal may consist of a perforation 63, Figs. 20 and 21, controlling the admission of air to passage 12 when coupled with a perforation 64 leading to one of the matrix-adjusting pins 65, Fig. 1, while the stopping-signal may consist of a perforation 66, controlling admission to the other justifier-passage 13, acting in conjunction with perforation 64. This will not interfere with the normal operation of the casting-machine, notwithstanding the fact that said pin 65 is part of the adjusting system, because no cast is made when pressure is admitted to either of the justification-passages 12 or 13. The relative location of the parts communicating with passages 12 and 13 is of course immaterial, and in order to avoid confusion extreme positions have been selected for the diagrammatic illustrations, Figs. 1 and 20. In practice it is customary to locate the port corresponding with passage 13 nearer the center, as indicated in Fig. 21, wherein is represented a section of controller-containing signals representing a complete line of composition, beginning with a leader-starting signal "63+64" and terminating with a leader-stopping signal "66+64." Next, as to the means for transmitting the signals from the controller to the leader. Secured to the main frame in proximity to the paper-feed for the controller is a frame 70, in which is supported a vertical shaft 71, provided with a cross-head 72. Each arm of said cross-head carries a retainer in the form of a pivoted latch 73, whose hooked head is adapted to engage a shoulder 74 on the frame. The rear ends of the latches are connected by a spring 75, tending to project their heads toward shoulders 74, and the latter are so related to the cross-head that when at one extreme of its oscillation one latch will be in engagement, and when at the opposite extreme the other latch will engage. Each latch 73 is also provided with an arm 76, which when its head is in engagement with its shoulder 74 will stand slightly beyond the face of the cross-head. Mounted in bearings on frame 70 is a horizontal shaft 77, supporting a pivoted frame, comprising two arms 78, connected by a web 79, and an independent lever 80, provided with a limiting stop-arm 81. Motion is transmitted from this lever 80 to arms 78 through a yielding connection, such as spring

82, interposed between said lever 80 and web 79, Fig. 6. Each arm 78 stands opposite one of the latches 73 and carries a pivoted tripping bar or link 83, whose free end is guided in the frame and supported normally below but in the same vertical plane with the disengaging-arm 76 of its latch 73, so that when either tripping-bar 83 is elevated into the plane of arm 76 and reciprocated it will by its engagement with said arm 76 first withdraw the latch from its shoulder and then turn the cross-head until the opposite shoulder is engaged by its latch. Lever 80 is also provided with a pivoted link 84, whose forward or free end is slotted longitudinally to permit independent motion of a normally reciprocating driving member, such as pin 85, and is furnished with a depression 86 to receive and engage said pin 85, and thus compel the link and its connected parts to follow the motions of said pin. As the timing of the main actuating-lever 87 of the die-centering mechanism is suitable for the purpose, the pin 85 is attached to said lever 87, and being prolonged over links 83 it serves to limit their vertical motions and retain them in line with the cross-head when elevated. Beneath each link 83 84 is located a cylinder 90, containing a piston 91 for effecting the elevation of the links into working position. One of the cylinders pertaining to links 83 is connected to the justification-designating passage 12 and the other to the justification-designating passage 13, while the cylinder of link 84 is connected to the selected leading-passage, such as that communicating with pin 65. When pressure is admitted to the cylinder of link 84, the latter will be coupled up with pin 85, thereby causing a reciprocation of links 83; but as the engaging ends of the latter are out of line with the arms of cross-head 72 the latter will not be disturbed. If, however, pressure is at the same time admitted to the cylinder of one of the links 83, the latter will be brought into position to engage first the latch and then the arm of the cross-head, thereby operating to shift the position of the latter from one extreme to the other, carrying with it shaft 71. This action will take place if the latch opposite the selected link 83 happens to be in its advanced position—that is, engaging its shoulder 74. Should it be in retracted position, no movement would be communicated to the cross-head.

As is obvious, the mechanism described is competent to interpretate the signals on the controller (composed of justification-signals plus a special or leading signal) and to convert them into movements of shaft 71 in opposite directions. Hence it only remains to be seen how said motions are caused to control the action of the leader.

The coupling-pin 50, by whose rotary movement the feeding of the leads is controlled, is provided with an extension 100, Fig. 14, angular in section and passing loosely through a link 101, Fig. 10, whose opposite end is piv-

oted to a switch-bar 102. This switch-bar is received in a way formed by two plates 103, attached to the galley-frame, and is provided with friction devices, such as springs 104, for retaining it in adjusted position. It is also provided at opposite ends with shoulders 105 106, of which the inner, 106, is the more prominent. Pivoted to the switch-bar on the inner side and in rear of the point of attachment of link 101 is a shunting-lever 107. This shunting-lever is furnished with two shoulders 108 109, between which is received a portion of switch-bar, thereby permitting a limited degree of independent motion, and the inner 15 edge of said shunting-lever is curved rearwardly and outwardly, as seen in Fig. 10, said curved portion overlapping the engaging face or portion of shoulder 106 when the shunting-lever is drawn to the left. The end 20 of the shunting-lever is, moreover, connected to a crank-arm on shaft 71, as through link 110, lever 111, and link 112, in such manner that when cross-head 72 is in one extreme position shunting-lever 107 will be drawn to 25 the left, Fig. 10, with its curved surface overlapping shoulder 106, and when in the opposite extreme position the shunting-lever will be moved back to uncover shoulder 106 and tilt switch-bar until its shoulder 105 is 30 projected across the path of the arm 113, carried by slide 9. When the parts are in normal position, as represented by full lines, Fig. 10, the feeding of the leads is suspended, because pin 50 is turned to withdraw its 35 arm 51 from notch 52 and arm 113 is free to reciprocate without engaging shoulder 105. When, however, the signal to begin leading occurs, shunting-lever 107 is moved back to uncover shoulder 106 and tilt switch-bar 102 40 until shoulder 105 is brought into the path of arm 113, so that as slide 9 moves outward to carry a completed line to the galley said arm 113 will by its engagement with shoulder 105 shift the switch-bar 102 longitudinally, thereby turning pin 50 and establishing 45 connection between the lead-feeder and its actuating devices. As slide 9 retreats after the delivery of the line to advance the line-carrier to position the lead fed to the 50 blade 6 is pushed forward to the galley in position to enter in advance of the next succeeding line. At the same time switch-bar 102 is reciprocated by the engagement of bar 113 with shoulder 106 to again disconnect the 55 feeding devices. This is done to facilitate the raising and turning back of blade 6 to permit access to the matter contained in the galley. So long as shoulder 105 remains in the path of arm 113 the feeding of leads will 60 occur during each reciprocation of slide 9, as explained. When, however, the signal to stop leading is reached, shunting-lever 107 is moved to the left, Fig. 10, so that its curved engaging surface overlaps shoulder 106 in the 65 path of arm 113. This does not immediately affect the position of switch-bar 102. Arm 113 again engages shoulder 105 and a lead is

delivered, as before; but during the return motion of slide 9 arm 113 operates through shunting-lever 107 to reciprocate the switch-bar and at the same time tilt it so as to withdraw the shoulder 105 from the path of arm 113, and thus interrupt the further delivery of leads upon the next stroke of bar 113.

The introduction of the shunting-lever 107 between the switch-bar and cross-head 72 instead of connecting the latter directly to said switch-bar, as might be done, is of importance as applied to a system in which the controller operates in the type setting or casting machine in the reverse order to that in which it was composed in that it permits the introduction of a lead after the signal to stop has become effective and, moreover, permits of the insertion of a single lead. To accomplish this, 85 it is only necessary that the starting-signal should be associated with the first justification-signal or the equivalent thereof and the stopping-signal with the second justification-signal or equivalent, in which event shoulder 90 105 will be presented to arm 113 when moving in one direction to effect the feeding and upon the return of said arm will engage the shunting-lever to withdraw shoulder 105, so that at the next reciprocation of arm 113 there 95 will be no delivery of a lead.

It should be explained that in practice the signal "lead" is applied to the controller immediately after the last solid line and before the first line of leaded matter is composed 100 thereon, and the signal "stop" is inserted at the conclusion of the leaded matter; but these signals are reversed at the type casting or setting machine, owing to the reversal of the controller, the signal "stop" being converted 105 into "lead" and "lead" into "stop."

Having thus described our invention, what we claim as new, and desire to secure by Letters Patent, is—

1. A controller for type-composing machines provided with special leading-signals for controlling the insertion of leads; substantially as described. 110
2. A controller for type casting and composing machines provided with leading-signals compounded of justification-designating signals and a selected signal; substantially as described. 115
3. In a type-composing machine provided with line-assembling devices and a controller, and in combination therewith a leading mechanism responsive to signals contained in the controller and governed thereby; substantially as described. 120
4. In a type-composing machine the combination with the line-assembling devices, of a leading mechanism and a controller in the form of a perforated record-strip, the latter governing the action of said leading mechanism; substantially as described. 125
5. In a type casting and composing machine governed in action by a perforated record-strip, the combination with said record-strip and the galley or line-assembling mechanism, 130

of a leading mechanism provided with controlling devices responsive to said record-strip, substantially as described.

6. In an automatic type casting and composing machine whose action is governed by a controller, the combination with the line-assembling or galley mechanism and a controller, of an automatic leading mechanism provided with means for throwing it into and out of action, and devices responsive to selected signals of the controller acting upon said leading mechanism to automatically govern the delivery of leads to the galley; substantially as described.

15 7. In an automatic type casting and composing machine the combination of the following elements, to wit; a controller provided with signals representing justification and leads; a galley mechanism responsive to the justification-signals; and a leading mechanism deriving motion from the galley mechanism and controlled, as to operation, by the lead-signals of the controller; substantially as described.

25 8. In an automatic type casting and composing machine the combination of the following elements, to wit; a controller provided with perforations serially arranged and representing individual types, line justification 30 and leads; a galley mechanism responsive to the justification perforations or signals; and a leading mechanism responsive to the lead perforations or signals but deriving its motions from the galley mechanism; substantially as described.

35 9. In a type-composing machine the combination of the following elements, to wit: a controller provided with lead-signals in addition to the normal signals; a galley or composing mechanism for assembling lines of type; a leading mechanism; means for actuating said leading mechanism; and means governed by the controller for automatically interrupting or disconnecting the leader-actuating devices at a period subsequent to the delivery accompanying the lead-signal; substantially as described.

10. In a galley mechanism for type-composing machines the combination with the galley, and line-transferrer, of a movable galley-blade normally closing the entrance to the galley and provided with a longitudinal channel, a lead-feeder delivering into said channel, and a pusher working in said channel to 55 transfer the lead to the galley; substantially as described.

11. In a galley mechanism for type-composing machines, the combination with the galley, line-carrier and line-transferrer, of a galley-blade movable substantially perpendicularly to the path of the line-transferrer and provided with a longitudinal channel, a lead-feeding device discharging into said galley-blade, and a pusher moving in unison with 65 the line-carrier to advance a lead opposite the galley as the line-carrier returns after de-

livering a line to the galley; substantially as described.

12. In a lead-feeding mechanism for type-composing machines the combination with the lead receptacle or channel and a pusher for discharging the leads therefrom, of a cut-off located opposite the discharge-opening and comprising a bar supported to move outwardly and upwardly under the pressure of the lead being discharged and held in contact therewith by spring-pressure so as to prevent the escape of superposed leads; substantially as described.

13. In a lead-feeding attachment for type-composing machines the combination with a lead receptacle or channel provided with a discharge orifice or slot and a shouldered pusher working therethrough and engaging the lowermost lead, of a cut-off supported on 85 links to move both vertically and outwardly with respect to the discharge-orifice and provided with an elastic tension member holding it toward said discharge-orifice; substantially as described.

14. In a leading attachment for type-composing machines the combination, to form an adjustable lead holding and feeding attachment, of the following elements, to wit: a bed-plate; two flanged housings or uprights 95 of which one is adjustably secured to the bed-plate and each is provided with a transverse bar forming the bottom of the lead-channel; a discharge-orifice immediately above said bar; a shouldered pushing-blade attached 100 to a bar supported in guides on each housing; a pivoted cut-off bar mounted on each housing; and actuating devices common to the two pushing-blades; substantially as described.

15. In a galley mechanism for type-composing machines the combination with a vertically-reciprocating longitudinally-channelled blade at the entrance to the galley, of a lead-feeding attachment located to one side of the galley and above said blade in position to deliver the leads into the latter; substantially as described.

16. In a galley mechanism for type-composing machines the combination with the vertically - movable longitudinally - channelled 115 blade at the entrance to the galley, of a lead-feeder located to one side of the galley and above said blade for delivering leads to the latter, actuating devices for said lead-feeder connected to the galley-blade, and a pusher reciprocating within the galley-blade; substantially as described.

17. In a galley mechanism for type-composing machines the combination with the galley and a lead-feeder, of a galley-blade provided 125 with a longitudinal channel open at the top near one end for the reception of the leads and open at the bottom at the opposite end for the discharge of the leads, and a pusher working in said channel; substantially as described.

18. In a galley mechanism for type-compos-

ing machines, the combination with the channeled galley-blade, of the pusher supported on a way attached to said blade and connected to its driving mechanism through a yielding trip device, substantially as described.

19. In a galley mechanism for type-composing machines the combination with the slide actuating the line-carrier and the reciprocating channeled galley-blade, of a lead-feeder, connected to and operating in unison with the galley-blade, and a lead-transferrer working in the galley-blade and connected to and operating in unison with the line-carrier slide; substantially as described.

15 20. In a lead-feeding attachment for the galley mechanism of a type-composing machine such as described, the combination with the lead-feeder, the pusher mounted and reciprocating upon the galley-blade and the 20 slide for actuating the line-carrier, of the link pivotally attached at one end to said slide and at the other to said pusher, said two points of attachment being in a line transverse to the direction of motion of the galley-blade, whereby as the latter is elevated the pusher will be retracted slightly; substantially as described.

21. In a lead-feeding attachment for the galley mechanism of a type-composing machine, the combination with the pusher carried by the galley-blade and the slide from which said pusher receives longitudinal motion, of the link pivoted to said slide and provided with a shoulder and a spring-actuated latch for engaging a pin on the pusher; substantially as described.

22. In a type-composing machine whose action is governed by a controller containing leading-signals, the combination of a leading attachment or mechanism provided with a 40 switching device for throwing it into or out of action, and an automatic signal-interpreter intermediate said switching device and the controller, whereby the latter determines the times and intervals of leading; substantially as described.

23. In a type-composing machine, the combination of the following elements, to wit: a leader; actuating devices for said leader including a switch for throwing the same into 50 or out of action; a controller; and means for actuating said switch from said controller, substantially as described, whereby the insertion of leads is governed automatically by said controller.

55 24. In a type-composing machine containing a galley or line-assembling mechanism, and a lead-supplying attachment therefor, the combination with the latter, of actuating devices controlled by a switch, a perforated controller, and a pneumatic signal-interpreter intermediate said switch and the controller; substantially as described.

25. In a type-composing machine the combination of the following elements, to wit: 65 line-assembling devices including a galley, a line-carrier, a line-transferrer and a galley-

blade; a leading attachment for inserting leads between adjacent lines provided with an actuating mechanism including a disengaging device for suspending the action of the leader; a switch adapted to be engaged by the line-carrier mechanism for actuating said disengaging member to stop or start the leader; and means for setting said switch; substantially as described.

75 26. In a type-composing machine the combination of the following elements, to wit: a galley or line-assembling mechanism; a lead-feeder provided with actuating means including a disengaging device for throwing the leader into and out of action; a switch-bar for actuating said disengaging device; means for setting the switch; and a movable member—such as arm 113—for engaging the switch to operate the disengaging device; substantially as described.

80 27. In a type-composing machine the combination with the disconnecting device for controlling the action of the lead-feeder, of a switch-bar pivotally attached to a link so that it can oscillate about either of two centers and provided with two shoulders; a reciprocating member—such as arm 113—for engaging the shoulders on the switch-lever, to reciprocate the latter; and means for tilting 90 said switch-lever to withdraw one of its shoulders from the path of the said reciprocating member; substantially as described.

85 28. In a type-composing machine the combination of the following elements, to wit: a leader whose actuating devices are connected to a driving member through a bolt capable of both longitudinal and rotary motions; a link partaking of the rotary motion of said bolt; a switch-bar pivotally connected to said link and provided with an engaging shoulder at each side of its point of attachment to the link; a reciprocating member—such as bar 113—adapted to engage the shoulders on the switch-bar when projected into its path; and means for tilting said switch-bar to withdraw 105 one shoulder from the path of said member; substantially as described.

90 29. In a type-composing machine and in combination with the disconnecting device of the leader-actuating mechanism, of the switch-bar pivotally attached to one end of a link and provided with engaging shoulders for co-operating with a movable driving member, such as bar 113, and a shunting-lever 110 pivoted to the switch-bar to one side of the point of attachment to the link and adapted to be projected into the path of the said driving member; substantially as described.

115 30. In a type-composing machine the combination of the following elements, for interpreting and transmitting signals from the controller to the leader, to wit: a reciprocating primary driving member; a driven member adapted to be coupled with said driving member; a second driving member coupled with the driven member; and means for coupling 125

up the primary driving and driven members, and the second driving member with its driven member; substantially as described.

31. In a type-composing machine the combination of the following elements, to wit: a primary driving member; a driven member adapted to be coupled with said driving member; a plurality of secondary driving members coupled with said driven member; a piston controlling the engagement of the said driven member and the primary driving member; and separate pistons for controlling the engagement of said secondary driving members with their transmitting members; substantially as described.

32. In a type-composing machine, as a means for interpreting and transmitting signals from the controller to the leader, the combination of the following elements, to wit: a primary driving member—such as pin 85; a driven member adapted to be coupled to said driving member—as through link 84; a plurality of secondary driving members—such as links 83—coupled to said driving member; pistons controlling the engagement of said driven and secondary driving members; and an oscillating transmitting member—such as cross-head 72—with which said secondary driving members coöperate—substantially as described.

33. In a type-composing machine, the combination with the leader-controlling devices, of a pivoted cross-head, two reciprocatory members—such as links 83—normally disconnected from said cross-head but each provided with means for shifting it into engagement therewith; a reciprocating driver and a

driven member—such as link 84—normally disconnected from said driver and provided with means for shifting it into engagement therewith and for transmitting motion to the two reciprocating members.

34. In a type-composing machine, as a means for transmitting signals from the controller to the leader, the combination of the following elements, to wit: an oscillatory cross-head whose arms are provided with retaining catches; three links connected to reciprocate in unison; a driving member; and a plurality of pistons, one for each link, operating through the links to connect the one to the driving member and the others to engage the catches and shift the position of the cross-head; substantially as described.

35. In a type-composing machine the combination of the following elements, to wit: an oscillatory cross-head; a reciprocatory link opposite each arm of the cross-head and movable into or out of engagement therewith, a reciprocating driving member overlying said links and forming a stop therefor; a third link detachably connected to said driving member and connected to the first-mentioned links through a yielding connection; and means for independently shifting each of said links from normal position into engagement with their opposing members; substantially as described.
